Primary Examiner—Sandra Morris

(57) **CLAIM**

The ornamental design for a school bus shoebox, as shown and described.

DESCRIPTION

FIG. 1 is a front perspective view of a school bus shoebox, showing our new design;

FIG. 2 is a partially exploded view thereof; and,

FIG. 3 is an isolated exploded view of the wheel storage compartment on the bottom of our design, shown broken away for ease of illustration.

1 Claim, 3 Drawing Sheets

FIG. 1

FIG. 2

FIG. 3
